UNITED STATES PATENT OFFICE.

FRED H. WIETHORN, OF CINCINNATI, OHIO, ASSIGNOR TO THE PERKINS-CAMPBELL COMPANY, OF CINCINNATI, OHIO, A CORPORATION OF OHIO.

BUCKLE.

Application filed May 18, 1927. Serial No. 192,377.

The object of my invention is to provide a simple and effective construction for buckles for belts, straps and the like, whereby the belt or strap may be held in any adjusted position without the use of holes.

Usually in buckles of this description, a serrated or smooth edged cam plate or clamping member is provided, but when in use, the belt is very apt to wear thin and smooth, and the clamping member fails to hold in the adjusted position, allowing the belt or strap to slip under the pressure. It is to remedy this defect in earlier constructions that my invention is particularly directed.

Another object is to provide a construction in which the operating member by which the clamp is applied may lie flat with the surface of the belt or strap.

These improvements are accomplished by 20 that certain novel construction and arrangement of parts to be hereinafter more particularly pointed out and claimed.

In the drawings:—

Figure 1 is a rear view of the buckle as 25 attached to a belt.

Figure 2 is a rear view of the buckle.

Figure 3 is a section taken on the lines 30 3—3 of Figure 2.

Figure 4 is a rear view of the buckle with 35 the operating bail thrown into full releasing position.

Figure 5 is a longitudinal section of the buckle plate with the cam plate and bail removed.

Figure 6 is a plan of the blank from which 40 the clamping cam plate is formed.

Figure 7 is a perspective view of the cam plate.

Figure 8 is a section perspective taken centrally of the cam plate.

Referring to the drawings, 1 is the front plate or body member of the buckle which is bent up at the sides to form side walls 2 and top flanges 3—3 to serve as a guide for the belt or strap. The inner ends of these flanges 45 3—3 are curved over to form a seat 4—4 for the pintle pin 5 upon which the operating parts are mounted.

Upon the pintle 5 is pivotally mounted the 50 cam clamping plate 6 formed from the blank 7 which is stamped out of a metal sheet with holes 8—8 and slots 9—9 and notches 10—10. The ends of the plate are turned up to form ears 12—12 through which the pintle 5 is 55 passed, and the body of the plate is curved

lengthwise on the line A, Figure 6 to form an engaging surface 13 for the belt and two outer wings 14—14 with an inner wing 15, this inner wing being curved to a greater extent than the outer portions, so that the contacting edge of 15 will be considerably lower than the edges of the parts 14—14. Also pivotally mounted on the pintle 5 inside the pivots of the cam plate is the bail 16. The buckle is attached to the belt 17 by a loop 18 60 over the bail and held by snap buttons 19.

The free end of the belt 20 is passed underneath the cam plate with the bail raised or thrown over against the flanges 3—3, which elevates the cam plate and gives free passage 70 for the free end of the belt. The cam plate is then turned down by rotation of the bail to a rearward position, the bail contacting with the parts 14, 14, to actuate the cam plate.

As shown in Figure 3, there are three engaging positions of the cam plate with the belt. If the belt is thick the middle portion 13 first engages the belt and clamps it to the plate 1, and as long as the engaging edge of 80 part 13 is to the rear of the pivotal center 5 of the cam plate, the belt will be held from slipping by this engagement. Should a thinner belt be used, the central portion 15 will then engage and clamp the belt and the 85 clamping power of part 13 will become ineffective.

Now as the belt wears smooth in use by pushing down the bail flat with the belt surface, which is permitted by reason of the 90 slots 9, 9, the parts 14, 14 will then come into clamping contact with the belt. Thus, with thick or thin belts the buckle can be used, and any tendency to slip as the belt surface wears smooth in use is effectively prevented.

Having thus described my invention what I claim as new and desire to secure by Letters Patent is:—

1. In a buckle, a buckle plate, a rotatable 100 cam element comprising a plate curved lengthwise, and provided with a plurality of notches to form a triple set of wings, one of said wings curved to a different extent from the other wings, whereby engaging surfaces will be provided at different distances from the longitudinal axis of the cam, means for rotatably mounting the cam on the buckle plate and a bail pivotally mounted with said cam plate, and adapted to bear thereon to 105 110

bring said engaging surfaces into action in succession with the belt attached to said bail.

2. In a buckle the combination with the face plate thereof, of a pintle held therein, 5 a clamping member secured to said pintle and formed of a lengthwise bent plate having one of its side edges at least formed into tongues bent at different angles, the edges of the plate so bent arranged to present engaging 10 edges to a belt to be retained against the under

surface of the plate in at least three distinct zones or lines, a bail also secured to said pintle, said clamping member being provided with clearance for the mounting of said bail, whereby the bail engages the clamping member and actuates it, said bail being provided for attachment of the opposite end of the belt from that which is to be clamped. 15

FRED H. WIETHORN.
